UNITED STATES PATENT OFFICE.

OSCAR E. BRIGGS, OF BINGHAMTON, NEW YORK, ASSIGNOR OF TWO-THIRDS
TO GEORGE HULL AND ALEXANDER D. WALES.

BRACKET-SEAT.

SPECIFICATION forming part of Letters Patent No. 315,598, dated April 14, 1885.

Application filed May 26, 1884. (No model.)

To all whom it may concern:

Be it known that I, OSCAR E. BRIGGS, a citizen of the United States, residing at Binghamton, in the county of Broome and State of New York, have invented certain new and useful Improvements in Bracket-Seats; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Similar letters refer to similar parts throughout the several views.

The object of my invention is to provide a bracket for a seat, table, shelf, or other purpose where a folding bracket is desirable, which will carry any reasonable load which can be placed upon it when adjusted in its proper position, and when not wanted in use folds away against the wall to which it is attached, and does not project from the wall 25 sufficiently to be unsightly or in the way when the room is desired for other purposes.

The drawings which accompany this application simply represent it when in use for a seat. I do not, however, limit myself to its 30 use for any single purpose, but claim the combination of devices here shown and described for any use or purpose to which it is applicable.

In the accompanying drawings, Figure 1 is an elevation showing the invention as attached 35 to the wall, and with a stool on the upper bar. The dotted lines in Fig. 1 show the position of the bars when partially folded, preparatory to closing up, showing where the different breaks take place when folded. Fig. 2 is a 40 perspective showing the device with the stool shown on Fig. 1 open, to form a back to the seat. Fig. 3 is a sectional view of the hinge which connects the two sections of the upper bar, with the catch to hold the hinge in place 45 and prevent the bracket from yielding when weight is placed on the upper bar.

In these different views A is the plate, which is fastened to the wall or standard; B, the shorter part of the upper or horizontal bar; C, the longer part of this horizontal bar;

D and E, the two sections of the lower bar which runs diagonally from the lower end of the plate A to the outer end of the bar C, forming a support for the horizontal bar B C. F is a brace between the bar E and the joint between the bars B and C. G is the stool which is used on the bracket when used for the purposes of a stool.

The bar C is made, preferably, with beveled edges, widest upon the upper side, and in connection with ribs attached to the bottom of the stool G, fitting to the beveled edges of the bar C, forms a dovetail, so that the stool G, or whatever attachment may be used in place of it can be moved back and forth on the bar C 60 as desired when in use, and moved up to the joint between C and B when the bracket is to be folded up. On the plate A are projecting hinge-joints to receive the corresponding joints on the bars B and E. At or near the center of 70 the bar E is a hinge-joint to receive the brace F, which also couples at the joint between B and C, thus preserving always the same distance between this joint and the middle of the bar E. In the joint between B and C the 75 joint attached to the bar C is made with a lip projecting backward, as shown at H, Fig. 3, and the bar B is cut away to allow this lip to turn where the vacant space is shown, Fig. 3. On the bottom of the bar B is a sliding bolt, 80 I, with spiral spring to throw it forward and keep it in place when in use, and passing down through the bar B is a button-headed rivet with a head on the top of the bar B, and the lower end of the rivet fastened in the bolt 85 I, and a slot in the bar B in which the body of the rivet travels. It will readily be seen that when this bolt I is thrown forward in place the joint between B and C will not rise, and that it rigidly holds the bar F. It is also 90 obvious that the joint between D and E will not break upward until the upper end of the brace is released; and since this joint is so constructed that it will not break downward, it follows that it can only be broken when the 95 joint between B and C is raised. Then, bearing in mind that all these joints are hinge-joints, the operation of the device can readily be seen. When it is desired to fold the seat or shelf against the wall or other surface to 100

which it is attached, the button J is pushed back, thus moving the bolt I backward and disengaging it from the jaw H, by which the joint between the bars B and C is released, 5 when a slight pressure upon the outer end of the bar C breaks this joint upward, the bars D, E, and F folding in, as shown by the dotted lines in Fig. 1, a continued pressure folding the whole up against the plate A, making 10 simply a flat surface against the wall.

When it is desired for use, it is only necessary to take hold of the stool or whatever may be attached to the bar C and lift upward and outward, when the bars drop into position, as 15 shown in Figs. 1 and 2, the bolt I is thrown forward by the spring, fastening over the jaw H, and the bracket is at once rigid.

When a table is to be substituted for a seat, two of the brackets can be used, thus forming 20 a strong and steady support for it.

The bracket can be made of any desirable metal, either iron or brass, cast or cut from plate metal, as may be found most desirable and economical in use.

Having thus described my invention and 25 the method of its construction and operation, what I claim as new, and desire to secure by Letters Patent, is—

A bracket consisting of a plate to fasten to a wall or standard, with a jointed horizontal 30 bar hinged to the plate at or near the top, in combination with a jointed diagonal bar pivoted to the lower end of the wall-plate and outer end of the horizontal bar, a brace between the diagonal bar and the joint in the 35 horizontal bar, a sliding bolt mounted on the horizontal bar to lock the same in an extended position, and a seat mounted on the outer end of said horizontal bar, all substantially as shown and described. 40

In testimony whereof I affix my signature in presence of two witnesses.

OSCAR E. BRIGGS.

Correction in Letters Patent No. 315,598.

It is hereby certified that in Letters Patent No. 315,598, granted April 14, 1885, upon the application of Oscar E. Briggs, of Binghamton, New York, for an improvement in "Bracket-Seats," the name of one of the assignees was incorrectly written and printed "George Hull," whereas it should have been *George E. Hall*; and that the proper correction has been made in the files and records pertaining to the case in the Patent Office, and should be read in the Letters Patent that the same may conform thereto.

Signed, countersigned, and sealed this 5th day of May, A. D. 1885.

[SEAL.]

H. L. MULDROW,
Acting Secretary of the Interior.

Countersigned:

M. V. MONTGOMERY,
Commissioner of Patents.
